UNITED STATES PATENT OFFICE.

JOEL U. ADAMS, OF CINCINNATI, OHIO.

BODY-BRACE.

SPECIFICATION forming part of Letters Patent No. 714,124, dated November 25, 1902.

Application filed June 16, 1902. Serial No. 111,832. (No model.)

To all whom it may concern:

Be it known that I, JOEL U. ADAMS, a citizen of the United States, and a resident of the city of Cincinnati, in the county of Hamilton 5 and State of Ohio, have invented certain new and useful Improvements in Body-Braces; and I do declare the following to be a clear, full, and exact description thereof, attention being called to the accompanying drawings, 10 with the reference-numerals marked thereon, which form also a part of this specification.

This invention relates to improvements in orthopedical and therapeutical garment appliances where metallic braces like steel bars 15 or springs are used which are attached to and carried by the body of a garment and incased in pockets, so as to form a part thereof, the object being to stiffen said garment more or less in certain places to suit certain 20 purposes.

My invention is shown applied to a so-called "shoulder-brace," an appliance worn on the back and provided with means, like straps and belts, to hold it in position. The body of 25 the garment appliance consists of suitable fabric, and in certain places the same is provided with bars of steel or other equivalent material to stiffen the body thereat, the object being to prevent, limit, or counteract 30 certain motions in certain directions to correct and straighten abnormal curvatures, &c. It is desirable that such garment should be washed from time to time, which operation, however, is greatly interfered with, if 35 not altogether made impossible, by the presence of these steel bars mentioned, which render the fabric unwieldy for washing purposes. Furthermore, if an attempt should be made to wash these appliances with the 40 steel bars in position the application of water would cause them to rust, whereby the garment would become stained and discolored. To overcome these objections is the aim of this invention, and the same is attained by constructing such an appliance in 45 a certain manner, which permits quick and convenient removal of these steel bars at any time and for any purpose, as for washing or renewal or to permit a number of such 50 garments to be folded up for packing and shipping, the construction being further such that said bars may be replaced with equal

facility by anybody not necessarily skilled in the manufacture of such appliances, so that for washing purposes the user may remove 55 them whenever desirable.

In the following specification, and particularly pointed out in the claim following, is found a full description of the invention, together with its manner of use, parts, and 60 construction, which latter is also illustrated in the accompanying drawings, in which—

Figure 1 shows such a body-brace, being a so-called "lace-back shoulder-brace," as it appears when attached in position, parts 65 of a human figure being shown in dotted outline, the device being supposed to be applied to the back of said figure. Fig. 2 is a horizontal section of the same. Fig. 3 is an enlarged cross-section through one of the steel 70 bars and the casing inclosing the same.

In the drawings, 5 indicates the body of the garment, of suitable fabric, there being two sections of it divided on a central vertical line, the edges thereof being drawn together 75 by a lacing-cord 6, tied at 7, straps 8 having first been passed forwardly over the shoulders and back again under the arms, where at 9 their ends attach to the lateral edges of the garment by suitable means, like buckles, 80 for instance. Below, a belt 10 is provided to hold the garment to the body. To stiffen this garment, there are provided flat bars 11, of steel or other equivalent material, which may be rigid or more or less elastic and 85 straight or curved or partly either to suit the particular therapeutical purpose intended. These bars are disposed to suit requirements and, as shown, they are arranged in an upright direction close to and parallel to the 90 edge of each section where they are laced to each other. To hold them in place, casings are provided for them of material which may be similar to the fabric of the body of the garment. They consist of strips 12 of such 95 fabric, with their edges parallel to the edges of the steel bars and parallel to the upright edges of the sections, but of sufficient width to permit when covering the steel bars a row of stitches 13 to be placed on the outside 100 of each edge of the steel bars, but within the edge of the strip of fabric, said stitches passing through this latter and through the body of the garment, and whereby said cas-

ings are completed. At one end, which may be either, these casings are left open to permit introduction or withdrawl of the steel bars. A flap 14 is provided to close this open 5 end, which may also be fabric or leather, which is turned over this open end, so as to close the same, and laps partly up on the outside over the casing, to which outside it is held by any suitable catch device, permitting 10 quick and convenient manipulation for opening or closing the flap to insert or remove a bar. The device I prefer to use for such purpose is the well-known spring-catch used as a glove-fastener and consisting of two complementary parts, one being substantially a 15 socket 15 and the other a button 16, received by the former. In Fig. 1 one of these bar-casings, the one on the left, is shown open, and the bar is partly pulled out. Parts of 20 said casing further up are also broken out to show the upper end of this bar. The other bar-casing is shown closed. When the bars are so pulled out, as shown, the garment becomes wieldly and pliable and may be readily 25 washed. It also prevents the bars from rusting, since they are not inserted again until the garment is completely dry. The insertion presents no difficulty and requires no skill, so that the user can readily do it at any 30 time.

Having described my invention, I claim as new—

A body-brace, consisting of two sections having parallel rear upright edges, a lacing-cord whereby they are connected to each other, means for attaching and holding these two connected sections in position on the body, a bar to stiffen the rear upright edge of each section and to provide for resistance thereat, strips of fabric or similar material 40 stitched at their edges to the upright edges of each section and parallel thereto, they being of sufficient width to permit introduction between the rows of stitches at each one of the edges of one of the bars mentioned, thus 45 providing casings for these latter, one end of each casing being left open to permit insertion or removal of the bar therein, a flap at one end of each of these strips adapted to close the open end of the casing thereat and 50 lap over the outside of such strip and a catch device consisting of two complementary parts, one part being secured to the outside of the strip forming part of the casing and the other to the inner side of the flap whereby this latter may be held in position to the outer side 55 of the strip forming the particular casing so as to close the open end of the same.

In testimony whereof I hereunto set my signature in the presence of two witnesses. 60

JOEL U. ADAMS.
